UNITED STATES PATENT OFFICE.

ANTON ZAHORANSKY, OF BADEN, GERMANY.

MACHINE FOR TREATING BRUSH STOCKS.

Application filed February 11, 1926, Serial No. 87,728, and in Germany February 11, 1925.

Brush stocks are sometimes drilled or bored, for the reception of the bristles, by means of a machine having a plurality of spindles and a plurality of work holders mounted side by side on a carrier or frame and rotatable about their vertical axes, the frame being arranged to rock about a shaft opposite the drills. In some known machines the frame carrying the work holders is also movable laterally and vertically parallel with itself. With these machines comparatively difficult and frequent adjustments are required, occupying much time, for the purpose of drilling the holes at different angles and so on, and even so they do not enable holes to be drilled at angles so acute as may sometimes be desirable.

The object of my invention is to remove these defects, and to this end I provide a machine wherein all the work holders are universally movable upwards and downwards, and to the right and left, and can also rotate about their vertical and horizontal axes, and be rocked as required about the shaft of the work holder carrier. The machine can be used not only for drilling, but also, if the appropriate tools are inserted, for cutting, trimming and so on. A similar arrangement of universally movable work holders, side by side or above each other, can be used also in a machine for inserting the bristles.

According to the invention the frame or carrier on which the work holders are mounted is not fixed directly to arms connecting it with the shaft opposite the tools, as has heretofore been usual, but is connected to a double armed lever, which is pivoted centrally to the arm and whose ends form gudgeons for the frame. This lever enables the frame in addition to rotating about its longitudinal axis to rock about an adjustable pivot remote from the shaft. Included with this device are various other mechanisms for adjusting and fixing the work holders and the frame which carries them.

A machine according to my invention is shown in the accompanying drawing, in which

Fig. 1 is a plan view thereof,

Fig. 2 an elevation,

Fig. 3 a section on the line A—B of Fig. 1,

Fig. 4 an elevation of part of the mecha-

nism including the frame with the work 55 holders, to a larger scale, and

Fig. 5 a plan view thereof,

Fig. 6 an elevation of the same part of the mechanism in another position,

Fig. 7 a section on the line C—D of Fig. 1, 60

Fig. 8 a section on the line G—H of Fig. 7,

Fig. 9 a section on the line E—F of Fig. 1, and

Fig. 10 an elevation of the mechanism shown in Fig. 9. 65

The frame 1 has guides for the bearings 2 of a horizontal shaft 3, upon which are two sockets 4, and in these sockets two radial arms 5 are mounted on pivots 6, so that the arms can swing sideways, as indicated by broken lines in Fig. 1. To each arm 5 there is pivoted a double armed lever 7, having arms of equal length, with gudgeons 8 at the ends thereof, supporting the frame 10 which carries the work holders 9. By means of the levers 7 the frame 10 can be rotated about a horizontal axis. It can also be moved sideways by rocking the arms 5, and can be raised and lowered by rotating the shaft 3.

Each work holder 9 is slidably connected 80 to a plate 11, the plate 11 being rotatable on the frame 10. The work holders are connected with each other by means of a rod 13 having eyes engaging studs on the plates 11. One work holder, which belongs to the series 85 but which I have marked 14 in the drawing, has fixed to it a slotted guide 15, in which there is a sliding and adjustable member 16 (Figs. 7 and 8) having two curved lateral arms and having also a tail piece 17 engaging a curved slotted member 18 fixed to the shaft 3. The member 16 has holes 16^a, with which a stud or pin 19 carried by the guide can be selectively engaged, to form a pivot about which the work holder 14 can be rotated. Rotation of the work holder 14 about this pivot causes all the other work holders to rotate. By selection of the hole 16^a into which the pin 19 is inserted the radius of 90 rotation of the work holders, in reference to their vertical axes, can be regulated, in order to regulate the lateral obliquity of the holes bored.

In the case of some brush stocks the holes are drilled at different angles. For this purpose the guide 15 is provided with a second pin 20, and the work holder can be swung alternatively on the pin 19 and on the pin 100

20, the pin 19 being disengaged in the latter case.

If the work holders are not to rotate about their vertical axes they are locked by 5 means of pins provided for that purpose.

If the work holders are not to rock about the shaft 3, but to move vertically and laterally parallel with themselves, two links 21, 22 (Fig. 3) connecting the frame 10 to 10 a rotatable spider 24 on the shaft, balanced by a weight 23, are locked by means of a pin 28 actuated by levers 25, 26, 27. To change over from parallel movement to rocking movement it is only necessary to disengage 15 the pin 28.

If the holes are to be drilled at angles more acute than is allowed for by rocking the work holders about the shaft 3 the double armed lever 7 is locked by means of a member 31 which is pivoted to a yoke 29 on the lever and is connected to a link 30; the latter has a slot, in which a pin 32 can be adjusted and fixed, this pin being rotatably engaged with a roller 34 which can travel in a guide 25 33. When the frame is swung the frame 10, with the work holders 9, is tilted on the pin 32, acting as a fulcrum, this pin being adjusted as required in the link 30.

For rotation of the work holders about 30 their transverse axes, or about axes close thereto, the frame 10 has a slotted arm 35 in which a stud 36 can be adjusted and fixed. This stud 36 can engage between either of 35 two pairs of parallel, vertically adjustable bars 37, so that by moving the work holder 14 the operator can rock the frame 10 into the position shown in Fig. 6, and can also rock it about the stud 36 when the latter is engaging the lower pair of bars 37. The 40 bars 37 can be rotated on a vertical spindle 38, enabling them to be folded back, and retained by a catch 39, when not in use.

If, for example, after rocking the frame on the spindle 32 (Figs. 4 and 5), it is to be 45 rocked about the stud 36, the pin 31 is withdrawn from the hole 31^a (Fig. 6), and then the bars 37 are moved into the position shown in Fig. 6.

Figs. 9 and 10 show mechanism for locking 50 the frame 10 after adjustment. The frame 10 carries an arc shaped member 40 against which a shoe 43 can be pressed by means of lever mechanism 41, 42. The frame 10 is locked by this means before the 55 shaft 3 with its associated mechanism is moved towards the drills 45. The pressure is applied by means of a treadle 46 and the levers 41 and 42, which move the shoe 43 in a guide 47 carried by the shaft, and when 60 the shoe encounters resistance the mechanism associated with the shaft is pulled forwards.

To prevent lateral rocking of the frame 10 when drilling laterally inclined holes there is a pawl 48 pivoted to the guide 47 65 and adapted to engage the member 40. For

lateral movement of the frame 10 the pawl must be lifted, as indicated by broken lines in Fig. 9.

The machine enables brush stocks of any kind to be drilled longitudinally and parallel 70 or from the centre in either direction, with holes distributed in any way, at varying angles, including angles much more acute than is usual. The stocks may be used for hair and clothes brushes, scrubbing brushes, 75 carpet brushes, brooms, brewers' brushes, nail brushes, including concave brushes, and so on.

What I claim as my invention and desire 80 to secure by Letters Patent of the United States is:—

1. A machine for treating brush stocks, having a horizontal series of tool holders, a horizontal, rotatable shaft parallel with said series of tool holders, two sockets on said shaft, having therein pivots perpendicular to the shaft axis, arms mounted on said pivots, to rotate with said shaft about the axis thereof, and also rotatable about said pivots, double armed levers pivoted to said arms for rotation about horizontal axes, a frame between said arms, rotatably engaged with said double armed levers, and a series 90 of work holders carried by said frame.

2. A machine for treating brush stocks, having a horizontal series of tool holders, a horizontal, rotatable shaft parallel with said series of tool holders, two sockets on said shaft, having therein pivots perpendicular to the shaft axis, arms mounted on said pivots, to rotate with said shaft about the axis thereof, and also rotatable about said pivots, double armed levers pivoted to said arms for rotation about horizontal axes, a frame between said arms, rotatably engaged with said double armed levers, rotatable carriers on said frame, work-holders on said carriers, and means for collectively rotating 100 said carriers.

3. The combination claimed in claim 1, together with a link, a removable pivot connecting said link to one of the double armed levers, a pin adjustable upon said link, a roller mounted on said pin, and a guide for 110 said roller.

4. The combination claimed in claim 1, together with a link connected to the work holder frame, a stud adjustable on said link, a slotted guide for said stud, and means for vertically adjusting said slotted guide.

5. The combination claimed in claim 1, together with a spider rotatable on the shaft, a balance weight attached to said spider, two links connecting two arms of said spider to the work holder frame, and means for locking said spider against rotation thereof.

6. The combination claimed in claim 1, together with a guide fixed to one of the work holders, a member slidable in said 130

guide, having a series of perforations and having curved, segmental arms, a curved slotted guide into which said perforated member engages, and a stud or studs carried by said guide adapted to engage said perforations to form a fulcrum for the work holder. 5

7. The combination claimed in claim 1, together with an arc shaped member fixed 10 to the work holder frame, a shoe adapted

frictionally to engage said member, a guide for said shoe fixed to the shaft, and lever mechanism for moving said shoe in said guide towards said arc shaped member and thrusting the frame, together with the shaft, 15 towards the tool holders by means of said shoe.

In witness whereof I have signed this specification.

ANTON ZAHORANSKY.
